US0D1066894S

(12) **United States Design Patent** (10) **Patent No.:** **US D1,066,894 S**
(45) **Date of Patent:** **** Mar. 18, 2025**

(54) **SHOE OUTSOLE BOTTOM**

- (71) Applicant: **Skechers U.S.A., Inc. II**, Manhattan Beach, CA (US)
- (72) Inventor: **Glen Chang**, Rancho Palos Verdes, CA (US)
- (73) Assignee: **Skechker U.S.A., Inc. II**, Manhattan Beach, CA (US)
- (**) Term: **15 Years**
- (21) Appl. No.: **29/928,608**
- (22) Filed: **Feb. 13, 2024**

Related U.S. Application Data

- (63) Continuation of application No. 29/915,835, filed on Nov. 4, 2023.
- (51) **LOC (15) Cl.** **02-04**
- (52) **U.S. Cl.**

(57) **CLAIM**

The ornamental design for a shoe outsole bottom as shown and described.

DESCRIPTION

FIG. 1 is a bottom perspective view of a shoe outsole bottom in accordance with my new design;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.

The grayed-out portions and surrounding dash-dash broken line boundaries in the drawings represent the unclaimed boundaries and portions of the shoe upper and shoe that form no part of the claimed design.

1 Claim, 7 Drawing Sheets
